(57) **CLAIM**

The ornamental design of a radial gate for use with a control gate, as shown and described.

DESCRIPTION

FIG. 1 is a front perspective view from above of an embodiment of a radial gate for use with a control gate.

FIG. 2 is a rear perspective view from beneath of an embodiment of a radial gate for use with a control gate.

FIG. 3 is a front view of an embodiment of a radial gate for use with a control gate.

FIG. 4 is a side view thereof.

FIG. 5 is a top plan view thereof; and,

FIG. 6 is a rear view thereof.

The claimed design is broken in the center to indicate indeterminate width.
